(57) **CLAIM**

The ornamental design for an “alphabet teaching device,” as shown and described.

DESCRIPTION

FIG. 1 is a front perspective view of an “alphabet teaching device” showing my new design;

FIG. 2 is a front elevational view thereof;

FIG. 3 is a bottom plan view thereof;

FIG. 4 is a rear elevational view thereof;

FIG. 5 is a right side elevational view thereof, the left side being the mirror image thereof; and,

FIG. 6 is a perspective view showing the device in its folded condition for carrying.
